UNITED STATES PATENT OFFICE.

EDWARD W. MEREDITH, OF REYNOLDSVILLE, PENNSYLVANIA, ASSIGNOR OF ONE-FOURTH TO EDGAR VERNON STEELL, OF CRENSHAW, PENNSYLVANIA.

FLUID-PRESSURE MOTOR.

1,158,525.

Specification of Letters Patent.

Patented Nov. 2, 1915.

Application filed January 7, 1915. Serial No. 948.

To all whom it may concern:

Be it known that I, EDWARD W. MEREDITH, a citizen of the United States of America, residing at Reynoldsville, in the county 5 of Jefferson and State of Pennsylvania, have invented certain new and useful Improvements in Fluid-Pressure Motors, of which the following is a specification.

The present invention relates to improvements in fluid pressure motors, and is designed especially for use in connection with brick making machines.

The primary object of the invention is the provision of facile, efficient and economical means for returning the table of brick making machines to normal position after the cut in the bricks has been made, but while the invention is specifically described in connection with machines of this character it 20 will of course be understood that the motor is equally applicable for use in connection with other machines in which this single acting piston motor is desired.

The invention consists essentially in certain novel combinations and arrangements of parts whereby the single acting piston is controlled and actuated to operate the motor, as will be pointed out hereinafter.

In the accompanying drawings I have 30 illustrated one complete example of the physical embodiment of my invention constructed according to the best mode I have so far devised for the practical application of the principles of my invention, and which 35 has proven highly satisfactory and efficient in actual practice upon brick making machines.

Figure 1 is a side elevation of a motor involving my invention. Fig. 2 is a longitudinal, horizontal, sectional view of Fig. 1, showing some parts in elevation, and the motor inert at the end of its working stroke. Fig. 3 is an end view of the motor. Fig. 4 is an enlarged horizontal longitudinal sectional view of the controlling valve and its casing showing the valve in position to furnish steam or other motive fluid to the cylinder to move the piston. Fig. 5 is a sectional view on line 5 5 of Fig. 4. Fig. 6 50 is a plan view of the controlling valve.

In the preferred embodiment of my invention I have illustrated the device as employing steam as the motive fluid, and while I shall hereinafter refer to the motive power

as steam it will of course be understood that other power such as compressed air might also be used if desired.

The piston stem 1 and its piston 2 are in direct connection with the table of the brick machine, at the threaded end 3 of the stem, 60 and it will of course be recognized that the table is a reciprocable one and is to be drawn to the right by the movement of the piston to the right in its cylinder 4 and moved to the left to return the piston, by other power 65 mechanism forming part of the brick machine. The cylinder is of usual construction and suitable dimensions and is equipped with the heads 5 and 6, the latter having a relief cock 7 opening into the cylinder to 70 regulate a cushion of compressed fluid in the end of the cylinder. The head 5 is provided with a stuffing box or gland 8 for the piston stem 1, and the heads are both secured to the cylinder by usual bolts and 75 nuts. The piston in the cylinder is a single acting piston, and as before stated its working stroke in the present showing of the invention is to the right, but the cylinder is provided with the usual end ports 9 and 10, 80 the former for admission of steam and the latter for exit of steam. The steam for actuating the piston is controlled by the piston valve 11 which is reciprocable in its casing 12 by power such as a cam or crank not 85 shown applied at the end of the valve stem 13. The casing, at one end, is in communication with the cylinder 4 through port 9 by the connecting pipe 14 which is the inlet pipe for live steam to the cylinder for operating the piston. A pipe 15 which also extends from the left end of the casing 12, passes around to the right end of the cylinder and communicates with its interior through the head 6. This pipe has a check 95 valve 16 therein and the communication is provided between the casing and cylinder to prevent the formation of a vacuum at the right end of the cylinder when the piston moves to the left.

As clearly shown in Figs. 2 and 4 the valve casing is provided with annular recesses or ports 17 and 18, the former for the inlet pipe to the cylinder, and the latter for exhaust from the casing, and this port 18 105 permits passage of exhaust steam to the exhaust pipe 19 of the casing. A third port is shown in the valve casing, indicated

100

105

at 20 and this port is in communication with the interior of the cylinder through the cylinder port 10.

In Fig. 4 it will be seen that the valve 11 has a passage 21 extending therethrough, open at the left end and closed at its right end by the threaded end of the valve stem 13; but at the right end of the piston valve its central bore is provided with four radial ports as 22 which establish communication between the interior of the valve casting and the interior of the valve itself. The valve is also cut away and its exterior diameter reduced to form an annular space 23 within the casing by means of which communication between the inlet pipe 24 to the casing and inlet pipe 14 of the cylinder through the port 17 in the casing.

The operation of the motor is as follows: Referring to Fig. 2 it will be seen that the piston 2 has finished its working stroke, having pulled the table to the right. Admission of live steam to the casing is cut off except to the space 23, and the pressure of steam throughout the cylinder pipe 14, the centrally bored valve 11 and pipe 15 is equalized, so that the return reciprocation of the table will move the piston to the left in Fig. 2. After the piston has been moved to the left, the piston valve is actuated and moved to the left also, as shown in Fig. 4. Now the live steam is admitted through space 23, port 17 and inlet pipe 14 to the cylinder at the left of the piston head, but passage of steam to the right in the casing or through the valve bore is prevented. However, steam is exhausted from the right side of the piston through the ports 10, 20 and 18 and outlet pipe 19, but a vacuum is prevented therein by the presence of the check valve 16 which provides for the re-

tention of a slight pressure of steam sufficient to prevent the vacuum. The admission of fluid pressure to the left of the piston of course moves it to the right and thus the working stroke of the motor is accomplished. The cushion at the right end of the cylinder 4 may be regulated by the position of the cock 7, and this may be determined by the requirements of different conditions.

What I claim is:

1. In a single acting motor, the combination with its cylinder and its piston, of a casing having a valve therein and a motive fluid inlet, ports at the ends of the cylinder in communication with the ports in the casing, said valve having means for equalizing pressure in the cylinder upon the return stroke of the piston and said valve adapted to admit motive fluid to the cylinder at one end and exhaust the same from the cylinder at its other end.
2. In a single acting fluid pressure motor, the combination with a cylinder and its piston, of a casing having a motive fluid inlet, exhaust port and end ports communicating with said cylinder, a piston valve controlling said ports and having a passage therethrough, whereby motive fluid may be furnished to one side of the piston, and exhaust fluid be withdrawn from the other side of the piston through said passage, and the pressure equalized in the cylinder on the return stroke of the piston.

In testimony whereof I affix my signature in presence of two witnesses.

EDWARD W. MEREDITH.
